150,352

DESIGN FOR A PENDANT OR SIMILAR ARTICLE

Paul Flato, New York, N. Y., assignor, by mesne
assignments, to D. Lisner & Co., Inc., New York, N. Y., a corporation of New York

Application June 25, 1947, Serial No. 139,905

Term of patent 3½ years

(Cl. D45—15)

To all whom it may concern:

Be it known that I, Paul Flato, a citizen of the United States of America, and residing at New York, county and State of New York, have invented a new, original, and ornamental Design for a Pendant or Similar Article, of which the following is a specification, reference being made to the accompanying drawing, forming part thereof.

Fig. 1 is a front elevational view of a pendant or similar article, showing my new design;

Fig. 2 is a top plan view of the pendant of Fig. 1.

I claim:

The ornamental design for a pendant or similar article, substantially as shown.

PAUL FLATO.
